(57) **CLAIM**

The ornamental design for a device for dispensing a liquid active substance, as shown and described.

DESCRIPTION

FIG. 1 shows a front perspective view of my design for a device for dispensing a liquid active substance;

FIG. 2 shows a rear perspective view thereof;

FIG. 3 shows a bottom perspective view thereof;

FIG. 4 shows a top view thereof;

FIG. 5 shows a top view of the base thereof without the removable bucket; and,

FIG. 6 shows a top view of the removable bucket.

The color in the drawings forms no part of the invention.
